DESIGN FOR A LATHE

Stanley W. Sparks, Norwalk, Conn., assignor
to The Sparks Machine Tool Corporation,
Norwalk, Conn., a corporation of Connecticut

Application July 2, 1941, Serial No. 101,857

Term of patent 14 years

To all whom it may concern:

Be it known that I, Stanley W. Sparks, a citizen
of the United States, residing at Norwalk, county
of Fairfield, and State of Connecticut, have in-
vented a new, original, and ornamental Design
for a Lathe, of which the following is a specifica-
tion, reference being had to the accompanying
drawings, forming a part thereof, and in which:

Figure 1 is a front elevational view of a lathe
embodying my new design;

Fig. 2 is a top plan view thereof;

Fig. 3 is a rear elevational view thereof;
Fig. 4 is an elevational view of the headstock
end thereof; and,

Fig. 5 is an elevational view of the tailstock end
thereof.

I claim:
The ornamental design for a lathe, as shown.

STANLEY W. SPARKS.
